COVERING FOR A LOUDSPEAKER ENCLOSURE

Gordon L. Duern, Kitchener, Ontario, Canada, assignor to Electrohome Limited, Kitchener, Ontario, Canada

Filed Sept. 17, 1971, Ser. No. 181,656

Term of patent 14 years

Int. Cl. D14—99

U.S. Cl. D26—14 G

FIG. 1 is a perspective view showing my design; and FIG. 2 is a perspective view showing the covering illustrated in FIG. 1 applied to a loudspeaker enclosure and constituting the front panel thereof, the remainder of the enclosure being shown in dotted outline to illustrate the environment within which a covering embodying my design may be used.

I claim:
The ornamental design for a covering for a loudspeaker enclosure, as shown and described.
